(57) **CLAIM**

The ornamental design for an attachment for grinding tool, as shown and described.

DESCRIPTION

FIG. 1 is a top perspective view of an attachment for grinding tool showing my new design;
FIG. 2 is another top perspective view thereof;
FIG. 3 is a bottom perspective view thereof;
FIG. 4 is a front elevational view thereof;
FIG. 5 is a rear elevational view thereof;
FIG. 6 is a top plan view thereof;
FIG. 7 is a bottom view thereof;
FIG. 8 is a right-side elevational view thereof;
FIG. 9 is a left-side elevational view thereof; and,
FIG. 10 is a top perspective view thereof, showing the environmental grinding tool and tungsten electrode.
The broken lines in FIG. 10 represent environment and form no part of the claimed design.
